UNITED STATES PATENT OFFICE.

EVELYN B. HAMLIN, OF CHICAGO, ILLINOIS.

INDUCTION-COIL FOR TELEPHONE SERVICE.

SPECIFICATION forming part of Letters Patent No. 350,130, dated October 5, 1886.

Application filed May 1, 1886. Serial No. 200,773. (No model.)

To all whom it may concern:

Be it known that I, EVELYN B. HAMLIN, of Chicago, in the county of Cook and State of Illinois, have invented a new, useful, and Improved Induction-Coil for Telephone Service, of which the following is a description, reference being had to the accompanying drawings, in which—

Figure 1 is a side view of my improved coil, a portion of the same being shown in section and broken away in order to show the different windings, and Fig. 2 is a central longitudinal sectional view showing the manner of constructing said coil, together with an outline or diagram of the connections of the respective sub-coils with the telephone service.

Like letters of reference indicate like parts in the different figures.

The object of my invention is to so construct an induction-coil for telephonic service that the current from a local battery may be utilized to induce a line-current upon a secondary or sub coil, and to amplify a local induced current in a third sub-coil, whereby I am enabled to eliminate the usual objectionable effects upon the receiving-instrument of line-induction, all of which is hereinafter more particularly described and claimed.

My improved induction-coil consists of four distinct windings or coils, the first and fourth of which are connected and are of low resistance, and the second and third of which are independent and of high resistance. The fourth is a continuation of the first, the two (first and fourth) being in direct circuit with a battery. Instead of describing these as first, second, third, and fourth, or primary, secondary, &c., I prefer to describe them as primary, (first,) primary induction, (second,) secondary induction, (third,) and primary extension, (fourth.)

In the drawings, A, Fig. 1, represents an ordinary insulating-spool surrounding the usual soft-iron core, B. I first wind upon said spool a primary coil, C, of large insulated wire, and then, suspending said winding, I place over said primary coil C a primary-induction winding or coil, D, of fine insulated wire, the terminals d d' , Fig. 2, of which preferably connect, respectively, with the line D'' and ground D''' . Around said primary-induction winding

I place a secondary-induction coil, E, of like or varying resistance to that of said primary-induction coil, but preferably the same, the terminals e e' of which may be connected with an ordinary magneto-receiver, F, as shown in Fig. 2, thus forming a local circuit therewith. Around said coil E, I then continue the winding of said primary coil C, thus forming a primary extension, C'. The convolutions of all of said coils are in the same direction, and the terminals c c' , respectively, of said primary and primary-extension coils are connected with the binding-posts g g' of a transmitting-instrument, G, in circuit with which a local battery, H, is interposed. The influence of a passing current through the primary coil C induces a current upon the coil D and line D'' , the return of which forms a local induced current upon the coil E in circuit, as stated, with the receiver F, the action of which local induced current is in turn amplified by the local-battery current upon the primary-extension coil C'. By this system of coils, and by thus placing the receiver, I am enabled to overcome certain difficulties and objections incident to the placing of said receiver directly in circuit with the line-wire. The disturbances which result from line-induction are largely avoided, while the sounds from the transmitting-instrument are thus rendered clearer and more distinct.

Having thus described my invention, what I claim, and desire to secure by Letters Patent, is—

1. An induction-coil consisting of a primary coil of coarse wire surrounding a soft-iron core, a primary-induction coil of fine wire, the terminals of which are designed to be connected with the line and ground, respectively, a continuous secondary-induction coil of fine wire, with the terminals of which a local circuit may be formed, and a primary-extension coil of coarse wire connected with said primary coil and surrounding the whole, the terminals of said primary and primary-extension coils being intended to be in circuit with a local battery, substantially as and for the purposes set forth.

2. In an induction-coil having the core B, the primary coil C, the coil D, connected with the line and ground, respectively, primary-ex-

tension coil C, connected with said primary coil, and the interposed coil E, arranged substantially as and for the purposes set forth.

3. The combination, in an induction-coil, of a soft-iron core, a primary coil of low resistance, continuous and independent primary and secondary induction coils of high resistance, and a primary-extension coil surrounding the whole and connected with said primary coil, substantially as and for the purposes set forth.

4. In a telephone service, an induction-coil consisting of a primary coil of coarse wire enveloping a soft-iron core, a primary-induction coil of fine wire having its terminals connected with a telephone-line and with the ground, re-

spectively, a secondary-induction coil of fine wire, and a primary-extension coil, said primary and primary-extension coils being connected with each other and in circuit with a local battery, in combination with a telephonic transmitter and receiver, the former of which is interposed in circuit with said primary and primary-extension coils and the latter with said secondary induced coil, substantially as and for the purposes described. 20

EVELYN B. HAMLIN.
